GRID CONTROLLED STORAGE TUBES

Stanley V. Forgue, Cranbury, N. J., assignor to Radio Corporation of America, a corporation of Delaware

Application June 29, 1951, Serial No. 234,202

18 Claims. (Cl. 315—12)

This invention relates to electron discharge tubes and in particular to a storage tube in which a signal may be stored as a charge pattern on a target electrode within the tube and utilized to provide output signals at a later time.

Such storage tubes have great utility in applications such as radar and systems in which information is derived electrically, and must be arranged to provide a visible pattern to an observer. Normally, such information is in the form of electrical signals which are used to provide a luminescent picture on an oscilloscope screen. However, in many cases the incoming signals are either too rapid to be clearly seen by the observer or consist of signal pulses, which must be arranged relative to each other to provide a composite picture on an oscilloscope screen. It is often desirable that signals of short duration be carefully studied or those that form a composite picture be retained on the oscilloscope screen sufficiently long for all of the picture to be put down. Accordingly, it is desirable to have a device which will store such incoming signal charges so that they may be used continuously for the desired length of time, or that they may be recalled at a future time to be compared with subsequent signals. Devices which make this possible are types of storage tubes which usually have a target electrode upon which the signals can be established and maintained until they are used.

It is an object of my invention to provide a storage tube for the storage of incoming signals to be used at a later time. It is another object of my invention to provide a storage tube having a target electrode of a nature that incoming signals can be stored thereon for any length of time desired by an observer. It is a further object of my invention to provide a storage tube having a target electrode with long storage time characteristics. It is also an object of my invention to provide a storage tube having a target electrode upon which incoming signals can be established and can be erased at will by an observer.

Specifically the invention is directed to an electron discharge device used for storing signals to be subsequently used. The tube includes a target electrode formed of a foraminous sheet having a dielectric layer on the surface thereof. Means are provided to store a charge pattern on one surface of the target sheet in accordance with signal information directed into the tube. A beam of electrons, formed by an electron gun within the tube, is used to read the stored charge pattern without erasing the pattern stored on the target electrode. One form of the tube has a writing gun on one side of the foraminous target electrode for putting down a charge distribution on the surface of the target electrode in accordance with signals applied to the control grid of the writing gun. On the opposite side of the target is arranged a reading gun for providing an electron beam of low velocity, which is scanned over the opposite surface of the foraminous target electrode. The reading beam will tend to pass through the openings of the target adjacent to positively charged areas of the target surface and will be completely reflected from

those portions of the target surface adjacent the charged areas. The reflected beam is thus modulated by the charge pattern on the foraminous sheet and is collected to provide the output signal of the tube. The tube may be operated to provide erasure of the charge pattern, at any time, or selective erasure of any part of the charge pattern. Also, the tube can be operated to provide a "holding" of the charge pattern on the target so that it may be read for an indefinite period of time. A modification of this structure is a discharge tube in which the charge pattern is established upon the foraminous target sheet either by photoemission from the target or by photoelectrons striking the target surface to provide a secondary emission from the target.

The novel features which I believe to be characteristic of my invention are set forth with particularity in the appended claims, but the invention itself will best be understood by reference to the following description taken in connection with the accompanying drawing, in which:

Figure 1 is a sectional view of an electron discharge device used as a storage tube in accordance with my invention.

Figure 2 is a schematic showing of several operating conditions of the tube of Figure 1.

Figure 3 is a diagrammatic showing of the secondary emission characteristics of an insulating material.

Figure 4 is a greatly enlarged showing of the target electrode of Figures 1 and 2.

Figure 5 is a schematic showing of operating conditions of a tube of the type of Figure 1.

Figure 6 is a sectional view of a picture storage tube in accordance with my invention.

Figure 1 discloses a storage tube in accordance with my invention. The tube comprises essentially a long tubular glass envelope 10 closed at the ends and provided with conventional type bases 12 and 14 respectively. Within the tube envelope is mounted a foraminous target electrode 16. The target may be of any type such as a thin metal foil having many openings therethrough or preferably a fine screen 18 of approximately 500 mesh per inch. Such a fine screen may be one formed as disclosed in U. S. Patent 2,529,080 of Harold B. Law. The metal screen 18 is supported within the tube envelope by a metal mounting ring, to which the screen 18 is welded or fastened by any means. The mounting of screen 18 on supporting ring 20 may be done in the manner disclosed in the copending U. S. application, Serial No. 167,410 of Harold B. Law, filed June 10, 1950, now U. S. Patent 2,654,940, granted October 13, 1953.

The foraminous target electrode 16 is coated with an insulating film 22 (Figure 4) of silica, for example. The coating may be done in several ways, such as by the evaporation of silica from a heated filament or by the decomposing of ethyl-silicate. Briefly the process involves heating the metal screen 18 in an atmosphere of ethyl-silicate and to a temperature to which the ethyl-silicate decomposes to form a deposit of silica over the surface of the wires of the metal screen 18. Other insulating materials have been used for coating wire screens. Such materials are lithium borate, glass enamel, and magnesium oxide, for example.

Within the tube envelope 10 there is mounted a writing gun structure 24 at one end of the tube and a reading gun structure 26 at the opposite end of the tube. The purpose of the writing gun 24 is to establish a charge pattern on the silica coated surface of the target 16 facing the gun. The charge pattern corresponds with incoming signals applied to the tube as described below. The purpose of the reading gun 26 is to provide an electron beam which will scan the opposite surface of the target elec-

trode 16 and provide an output signal corresponding to the charge pattern on the target.

Essentially, the writing gun 25 is of a conventional type and consists of a cathode 25, a control grid 28 and an accelerating grid 30. The cathode 25 is essentially a metal tube closed at the end facing target 16, which end is coated with electron emissive material to provide a source of electrons. The electrons are formed into a beam by electrodes 28 and 30 and directed toward target 16. Between gun 24 and target 16 are mounted additional electrode structures consisting of a long metal tubular electrode 32, which may be connected to accelerating electrode 30 of the gun. Between electrode 32 and target 16, is mounted a screen or collector electrode 34, supported by a ring 36 and closely spaced from the coated target mesh 18.

The electron beam of gun 24 is focused to a well defined spot on the surface of the target 16 by a focusing coil 38 coaxially mounted about the tube envelope 10. The focusing operation of coil 38 is well known and is not described in detail here. Also, surrounding the envelope 10 and adjacent gun 24 is a neck yoke 40 comprising two pairs of oppositely disposed magnetic coils for providing a pair of deflecting fields at right angles to each other. As is well known, the coils of each pair of coils are connected respectively in series to a source saw-tooth voltages for providing respectively line and frame scansion of the beam of gun 24 over the surface of target 16. The several electrodes of gun 24 are connected to a source of potential through a voltage divider 33, to provide the different voltages required for gun operation. Control grid 28 and accelerating grid 30 are coupled to cathode 25 through voltage sources 35 and 37 respectively.

The reading gun 26 is similar to gun 24. The cathode of gun 26 (not shown) is operated at ground potential which is the potential of the metallic screen 18 of target 16. The electron beam of gun 26 is accelerated to a velocity of several hundred volts by an accelerating electrode 44. An extension of coil 38 provides a focusing field between gun 26 and target 16 to bring the electrons of the beam to a fine spot on the surface of target 16. A tubular electrode 46 provides a substantially field free space between electrode 44 and target 16 and prevents the glass envelope wall from charging up during tube operation. Electrode 46 may be maintained at the same potential of the accelerating grid 44. A neck yoke 45 represents deflecting coils for scanning the beam of gun 26 over the surface of target 16, in a well known manner.

Adjacent target 16 and between gun 26 and the target is an open screen 48 supported by a ring 50. Screen 48 is of high transmission and is maintained at around 180 volts above ground potential during tube operation. Since the metal screen 18 of target 16 is at ground potential, screen 48 provides a uniform decelerating field in front of the target, to slow down the beam of gun 26 to essentially zero velocity. The electrons of the beam approach the dielectric surface of target 16 with very little energy. Due to the velocity range of the electrons in the beam some of the beam electrons will strike the coated surface of screen 16 with a volt or so of energy. Under these conditions the secondary emission from the dielectric coating is less than 1, and the dielectric coating will be driven slightly negative to a volt or so below ground potential. At this point, all of the beam electrons are reflected back toward gun 26. Due to the focusing field of coil 38, these reflected electrons will travel back toward the positive accelerating grid 44 along substantially the same path that they took on their approach to target 16. The reflected electrons will strike the surface of accelerating grid 44, which is normally treated to provide a high secondary electron emission. This secondary electron emission is pulled

through the several stages of a multiplier section 52 to produce a many-fold amplification of the beam electrons, the secondary electrons of the multiplier are collected by a multiplier collector electrode 54. The details and operation of the particular multiplier shown in Figure 1 are fully set forth in U. S. Patent 2,433,941 of P. K. Weimer. The several electrode parts of gun 26 as well as the electrodes 46 and 48 are adjustably connected, as shown in Figure 1, to the voltage source 33.

OPERATION 1

Writing

As indicated in Figures 1 and 2 the metal screen 18 of the target electrode is maintained during tube operation at ground potential. To "write" a signal pattern on target 16, the cathode of gun 24 is held at around 300 volts negative with respect to ground potential. Collector screen 34 is operated at around 150 volts positive with respect to ground potential. In this manner, then, the electron beam of gun 24 is accelerated to a high velocity by the potential of the collector screen 34, which is substantially 450 volts positive with respect to the cathode electrode 25.

As the beam of gun 24 is scanned over the dielectric surface of target 16 the electrons of the beam will strike the target surface at high velocities. The energy of the electrons will be between 300 and 450 volts. The electrons striking the silica film 22 of target 16 will initiate a secondary electron emission from the bombarded area greater than the number of the electrons striking the area.

There is shown in Figure 3, the relationship between this ratio of the number of secondary electrons leaving a dielectric surface to the incident bombarding electrons. The vertical axis of the diagram of Figure 3 represents the ratio of the secondary electron emission current to the incident electron beam current. The horizontal axis of the diagram of Figure 3 represents the energy in electron volts of the incident electrons. Curve 41 indicates that, at a given voltage, the secondary emission ratio is unity, as represented by the horizontal line 42. At this voltage, as many secondary electrons leave the bombarded surface as incident electrons strike the surface. The curve indicates that the secondary emission ratio increases with an increase in the energy of the bombarding electron beam to a certain point, from which the secondary emission decreases with further increase of beam energy. Where curve 41 initially crosses line 42 is known as the first crossover point.

The secondary emission from the dielectric coat 22 of target 16 is collected by the mesh screen 34. The bombarded areas of target 16 will be rapidly driven positively by the secondary emission therefrom and will be raised to a positive potential close to the 150 volt potential of screen 34.

A bombarded area of the dielectric surface of film 22 will not be driven above the potential of screen 34, since the secondary electrons leaving the bombarded dielectric film 22 will be collected by screen 34 only as long as the collector screen is more positive than the surface of the silica film 22. If a bombarded area of silica film 22 tends to go above the potential of collector screen 34, screen 34 will then present a negative field to secondary electrons leaving the bombarded areas. These secondary electrons will be reflected by this negative field and fall back onto the surface of target 16. In this manner, the collector screen 34 establishes an equilibrium potential to which the bombarded portions of the dielectric film 22 are driven by the electron beam of gun 24.

To "write" a signal pattern on the dielectric surfaces of target 16, the beam of the "reading" gun is first scanned on the target 16 to drive all portions of the dielectric film 22 substantially to ground or gun cathode potential. A pattern of charges may then be established on the

dielectric surface of the foraminous target 16 by modulating the electron beam of gun 24, as it is being scanned over the surface of the target. For example, incoming signals to be stored are first amplified by an amplifier tube 56 to provide signal voltage pulses which are applied between the cathode 25 and the control grid 28 of gun 24. If the grid 28 is previously held negative to cathode 25, to cut off the electron beam, any incoming signal voltages applied to grid 28 will pulse the grid above its cutoff potential by varying amounts to provide modulation of the electron beam in accordance with the signal pulses applied. Such modulation of an electron beam is well known. The modulated beam, as it is scanned over the dielectric surface of target 16, at each elemental area struck by the beam will drive the dielectric target toward the equilibrium potential established by collector screen 34, in accordance with the operation described above. The areas of the dielectric target film 22, not struck by the beam will remain at substantially ground or at the potential of the cathode of gun 26. Thus the "writing" beam of gun 24 establishes a pattern of differently charged areas on the target surface. This charge pattern, in the direction of beam scansion and at each elemental target portion, corresponds to the successive signal pulses applied to the writing gun control grid as the beam scans the target area.

Reading

After the charge pattern has been established by gun 24 on target 16, gun 24 may be turned off, and the pattern will remain on the target because of the high insulating properties of the silica coating 22.

The charge pattern on target 16 can be reproduced as an output signal which will correspond to the input signal applied to gun 24. This is accomplished by scanning the beam of the reading gun 26 over the target 16.

Figure 4 discloses a greatly enlarged sectional view of a portion of the target 16 of Figure 1. The positive areas established on the surface of target 16 by the beam of gun 24 provide positive fields which extend through the adjacent openings of the screen 18 to reduce, in those areas, the negative reflecting field originally established on the dielectric film 22 by the beam of gun 26. In Figure 4, for example, it is assumed that the area bracketed by A has been charged positively by the "writing" beam. The positive field of this charged area extends through the openings of screen 18. As the beam of gun 26 scans across the target portion A, it will "see" the positive field and will be drawn through the openings in the screen 18. In areas B and C of Figure 4, it is assumed that no positive charges have been established by the beam of gun 24 on the target. In these uncharged areas, the beam of gun 26, will be reflected back toward gun 26. Thus, as the beam of gun 26 is scanned over the charged target 16, the beam will be robbed of electrons in those target portions which have a positive charge thereon, but will be totally reflected by the negative areas or uncharged areas of the target surface. In this manner, the electron beam returning to gun 26 will be modulated in accordance with the charge pattern established by the beam of gun 24 on target 16. This modulated return beam is amplified by the multiplier section 52 to provide a voltage signal pulse in the circuit of multiplier collector electrode 54. This voltage pulse is amplified by any well known means, such as a circuit including an amplifier tube 58, the control grid of which is coupled to the multiplier collector electrode 54. The electrons of the beam of gun 26, which penetrate through screen 18 in the positively charged areas, are urged toward the positive collecting screen 34, where they are mostly collected.

The output signal of the tubes of Figure 1 can be used to modulate the beam of an oscilloscope tube or a television picture tube upon the fluorescent screen of which the charge pattern can be observed as a corresponding visual pattern. The scanning of the beam of the oscillo-

scope tube must be synchronized with the scanning of the beam of gun 26.

Erasing A

It is desirable to be able to erase the charge pattern from target 16 either completely or partially in order to apply additional information to the target. A satisfactory method of providing erasure of the charge pattern is to ground the collector screen 34 (Figure 2) and scan target 16 with the full writing beam, in the manner described. The writing beam will still strike all portions of the dielectric surface 22 of target 16, at an energy above first crossover. The secondary electrons from all areas of the dielectric film 22 are now reflected back on the target surface by the negative field of collector screen 34 and will establish all of the dielectric film 22 scanned by the writing beam at ground potential. This method of erasure is effectively that of changing the equilibrium potential of the dielectric surface of target 16 from 150 volts positive to ground potential. After erasing the charge pattern, collector screen 34 may be reset at 150 volts positive with respect to ground and a new set of signals can be used to establish another pattern of positive charges on target 16.

Erasing B

Another method of effecting erasure of the charge pattern on target 16 is that in which the potential of collector screen 34 is reduced to a point where reading beam electrons from gun 26, which penetrate screen 16, will be reflected back onto the surface of the target 16. The writing gun 24 is turned off (Figure 2) during this operation. With the potential of screen 34 below ground, for example, the reading beam electrons will be turned back onto the target surface. Also, any secondary emission from the target will be suppressed by the negative screen 34. Thus, the reading beam electrons will rapidly drive the surface of target 16, facing the screen 34, to an equilibrium potential equal substantially to that of ground.

Slow erasure

A method of slow erasure by the reading beam is also possible. The potential of collector screen 34 is lowered to a point where only a portion of the reading beam is reflected back onto the target screen 16. If the reflected portion of the reading beam is small then the reading beam electrons falling back onto the target 16 will only slowly erase the charges established on the target. In this operation, the writing beam can be used to reestablish any desired portion of the charge pattern, while undesired portions will slowly disappear.

This operation of slow erasure is of value in systems such as radar. In such an application, the scanning yoke 50 of gun 24 is arranged to provide a PPI type scanning of the beam of gun 24 over the target surface 16. This type of scanning is well known and is synchronized with the radar antenna, so that the beam of gun 24 may put down on the target surface a charge pattern in accordance with the incoming radar signals. The out-put signal of the tube is applied to the control grid of an oscilloscope tube to provide a visual picture of the charge pattern on target 16. With the described method of slow erasure, the picture of moving objects on the radar oscilloscope screen will gradually disappear over an adjustable length of time, while the picture of stationary objects, which are repeated, will be retained on the oscilloscope picture.

Selective erasure

Parts of the charge pattern on target 16 may be erased selectively by scanning the beam of gun 24 only over portions of the target surface which are to be erased. This can be accomplished by manual control of the horizontal and vertical deflecting fields of yoke 40. An operator, by watching the picture of the charge pattern on an oscilloscope tube, can with little practice, direct the beam of gun 24 to any portion of the target which is to

be erased. For this operation, the erasing conditions of the tube must be established, to use either the writing beam electrons or the reading beam electrons for erasing.

When gun 24 is used, as described above for erasing the charge pattern, the beam also may be so defocused that the electrons of gun 24 reach the target not as a beam, but as an electron spray, covering the whole target area. This method of erasure does not require scanning the beam over the target surface.

Holding A

It is desirable at times to maintain the charge pattern on target 16 for a desired length of time. Also, if the signal pattern on 16 is read for a considerable length of time, the pattern becomes somewhat indistinct. This is due to the conditions existing during tube operation, in which electrons from the reading beam fall on the charged areas of target 16 and gradually drive them down in potential. Also, there is a small amount of current leakage through the silica film 22 between the grounded wire screen 18 and the positively charged areas of the film, which must be considered if storage times in excess of a few hours are valued. It is thus, desirable often to sharpen the image by restoring the charge pattern to its original condition. Both of these results have been accomplished by periodically raising the cathode of gun 24 to ground potential accompanied by a corresponding increase in the potential of the other electrodes of gun 24 (Figure 2). With screen 34 held at its collecting potential of 150 volts, the beam of gun 24, is scanned over target 16. The beam will strike the charged areas of target 18 at above first cross-over to drive them to the equilibrium potential of screen 34. Also the beam will strike the areas of target 16, which have not been written on, below first cross-over to drive them back to ground potential. In this manner, the charge pattern is restored or retained on the surface of target 16.

Holding B

Another method of holding or restoring the charge pattern on the target is possible with the cathode of gun 24 set at about 300 volts negative with respect to ground and with screen 34 set at 150 volts positive with respect to ground (Figure 2). By directing the writing beam at the support ring 20 of target 16, the beam of gun 24 will strike ring 20 at above first cross-over to provide a cloud of secondary electrons of relatively low velocity. Those areas of the target, which have been written upon will be at a potential greater than first cross-over above the potential of ring 20. Thus, secondary electrons from ring 20 will strike these areas at potentials to initiate a secondary emission therefrom greater than unity. This will restore the charged areas to equilibrium potential, which is substantially that of collector ring 34. Those secondary electrons from ring 20 falling upon the un-written or uncharged portions of target 16 will land thereon at below first cross-over and will maintain them at ground potential. In this manner then, the original charge pattern can be restored by periodically striking ring 20 with the high velocity beam of gun 24.

The tube of Figure 1 may be operated under slightly different conditions than those described above, to provide somewhat similar results. For example, screen 18 of target 16 can be maintained at any potential, during tube operation, between ground and first cross-over. However, it is set as low as possible so as to minimize charge leakage between the surfaces of the silica coating 22. It is desirable that this leakage through the silica film 22, be at a minimum. In practice it is low enough to allow a storage time of a few hours or less. The invention need not be confined to magnetic focusing and deflection of the electron beams, as both electrostatic focusing and deflection may be used instead. Target screen 16 may also comprise a foraminous conductor with an insulating coating only on the writing gun side. In this case the

foraminous conductor can be set at a potential to just reflect the reading electron when there is no charge on the writing side.

OPERATION 2

The tube of Figure 1 may also be operated under different conditions than those outlined above in Operation 1. The collector grid 34 is set at substantially 20 volts positive with respect to ground (Figure 2). In writing the charge pattern on target 16, the reading gun is first scanned over the target surface to drive the dielectric coating 22 to substantially cathode or ground potential. The writing gun is operated with a cathode potential of nearly -500 volts negative with respect to ground. The writing beam is scanned over the target surface while the input signals are simultaneously applied to the control grid 28 of the gun to modulate the writing beam. Wherever the modulated writing beam strikes the target surface it will charge the surface of the dielectric film to substantially collector screen potential of around 20 volts positive, while the areas not struck by the writing beam will remain at substantially ground potential. The establishing of the charge pattern is due to secondary emission from the target surface in the manner described above. The reading takes place in the normal manner described above.

Erasing

Both the above described methods of erasing, A and B can be used with this operation 2. However, it is also possible to erase the charge pattern by grounding the writing gun cathode 25 (Figure 2), so that the writing beam, when it is now scanned over the target surface, will bring both the charged and the uncharged target areas to cathode potential, since the writing beam will strike the target surface with a velocity at which the secondary emission ratio is less than 1. In erasing the target with the writing gun, it is not necessary to use a sharp focus of the beam on the target but the beam can be defocused and scanned over the target. Also, the writing gun potential can be adjusted to provide a broad beam of electrons covering all of the surface of the target.

Holding

With Operation 2 a new method of holding the charge pattern on the target surface may be used. The cathode of the writing gun can be set at some negative potential so that the areas of the target surface which have been charged to around 20 volts positive are struck by the beam with an energy which is above first cross-over, while the uncharged areas at substantially ground potential will be struck by the beam below first cross-over.

As indicated in Figure 1 by the dotted circuit 59, it is possible to collect the output signal from the tube from the collector mesh screen 34. In the charged or positive areas of the foraminous target 16, the reading beam electrons will pass through the target to the collector screen 34 as described above. These reading beam electrons collected by screen 34 can constitute the output signal pulses of the tube by connecting the collector mesh screen 34 into the amplifying circuit 59.

OPERATION 3

Screen 34 may be connected to the input amplifying circuit connected to the tube so that incoming signal pulses are applied to the collector screen 34 while the writing beam is scanned over the target surface. During this type of operation (shown in Figure 5) screen 34 is first set at ground and the writing gun cathode at around -500 volts relative to ground. The input signals may be amplified so that the maximum signal will swing grid 34 to either 20 volts positive with respect to ground or 100 to 150 volts positive with respect to the ground. Thus, the writing beam will maintain the target areas that it strikes at ground when there is no signal on screen 34. But with a signal pulse on the screen the writing beam

will drive the dielectric target surface to whatever potential the collector screen 34 is raised by the input signal. Thus, there is established on the target surface a charge pattern varying from ground to 200 volts positive in one case or from ground to 100 to 150 volts positive in the other case. The holding and erasing techniques described above for Operations 1 and 2 may be used in the operation of the tube under these conditions wherever applicable.

Slow erasure

Another method of slow erasure is disclosed in the tube of Figure 5. As the reading beam electrons which penetrate screen 16 strike screen 34, a certain number of secondary electrons are initiated. These electrons normally are urged by the positive field of wall 32 through screen 34 and are collected by the various positive electrodes of the tube. However, it is possible to redirect these secondary electrons from screen 34 onto target 16 by lowering the voltage of the wall 32. These secondary electrons slowly drive the target surface toward ground potential. A disadvantage of this particular procedure is however, that in changing the voltage of electrode 32 the writing beam is defocused and requires that the field of coil 38 be readjusted to reestablish the focus of the beam. Furthermore changing the field of coil 38 will defocus the reading beam of gun 26. A more satisfactory arrangement is to provide an additional screen 59, mounted between gun 24 and the collector screen 34 and independent of the wall electrode 32. During normal tube operation, screen 59 may be given the same potential as the wall electrode 32 which is around some 200 volts positive with respect to ground. However for slow erasure the screen 59 may be lowered to a potential which will suppress the secondary electrons from screen 34 and urge them toward the target electrode 16. The use of screen 59 thus eliminates the complications of defocusing the electron beams of the tube.

Half-tone operation

As described above, any surface of target 16 struck by electrons of the writing beam is driven positively to equilibrium or collector screen potential. Under these conditions, the reading beam will resolve all charged areas of target 16 by equal signal values. However if the "writing" beam is modulated with signal voltages ranging upwards from cutoff potential, it is possible to establish a range of charges on target 16 from a minimum, at ground potential, to a maximum near collector screen potential. The reading beam then can resolve such intermediate potentials on the target to provide half-tone signal pulses in the output circuit.

To provide half-tone operation of the tube of Figure 1, use is made of the velocity distribution range of the reading beam electrons. The potential of screen 34 is adjusted to a positive value of a few volts above ground. The writing gun is modulated by the incoming signals and simultaneously scanned over the target surface to establish a charge pattern thereon. The secondary electron emission from each elemental area of the target surface will be proportional to the number of primary writing beam electrons striking the respective area.

The D. C. grid bias of the writing gun is chosen so that, when the modulating signal makes it a maximum, the beam can charge the target capacity under the beam in a positive direction to a potential sufficient to allow the slowest electrons of the reading beam to penetrate the target. As the modulating signal becomes increasingly more negative, fewer writing beam electrons are available for charging the target. The potential swing of the target thus becomes ever smaller and fewer reading beam electrons can penetrate the target.

That portion of the reading beam returned to gun 24 will then be modulated in accordance to the range of potentials on target 16 to provide half-tone signals in the output circuit of the tube.

Picture storage tube

Figure 6 discloses a storage tube having parts and operation similar to that described for the tube of Figure 1. In this tube, the charge pattern is established on the target surface by photoemission from the target screen or by secondary emission therefrom initiated by photoelectrons striking the target. The tube includes an envelope 60 having a flat optically transparent face plate 62 closing one end thereof. On the inner surface of face plate 62 is a photoemissive film formed for example, of a sensitized silver-oxide. Spaced along the tube axis from photo-surface 64 is the target electrode 66 comprising a foraminous metal sheet or screen coated with a thin film of silica as described above for target 16 of Figure 1, and may be a 230 mesh stainless steel woven screen coated with a thin film of silica. Between target 66 and the photocathode film 64 is mounted a tubular accelerating electrode 68 supporting a high transmission screen 63 adjacent the plate cathode 64, for directing photoelectrons from surface 64 toward target 66. A focusing coil 72 is mounted coaxially to and surrounding the tube envelope 60. The magnetic field provided by coil 72 maintains the photoemission from film 64 in substantially parallel paths in its passage to target 66. A secondary electron collector screen 74 is mounted closely adjacent to target 66 by a support ring 76. Collector screen 74 corresponds in function to collector 34 of Figure 1.

The reading portion of the tube of Figure 6 is substantially the same as that described in Figure 1. However, the gun portions and the multiplier section are shown in greater detail. Briefly, the reading gun 80 comprises a cathode structure 82, control grid 84 and accelerating grids 86 and 88. In the manner described for Figure 1, the electron beam formed by gun 80 is directed toward target 74 through a tubular wall electrode 90 and decelerating electrode 91 having an open screen 92 mounted adjacent target 66. Screen 92 corresponds to screen 48 of Figure 1. The electron beam of gun 80 is scanned over the target surface by deflecting coils represented by the neck yoke 97. Focusing coil 72 extends to gun 80 and provides a magnetic focusing field of the beam of gun 80 onto the surface of target 66.

The several electrodes of the tube are operated at the voltages shown in Figure 6. These voltages are not limiting but are representative of those which have been used in a tube of this type. The beam of gun 80 scans the silica coated surface of the foraminous target 66 forcing gun 80 to drive that surface to substantially ground or gun cathode potential. At this potential, the surface of target 66 reflects the remaining portion of the beam back toward gun 80. The reflected portion of the reading beam strikes the surface of accelerating electrode 88 with sufficient energy to provide secondary emission therefrom, which is directed by a persuader electrode 93 into a multiplier section 94 surrounding gun 80. Multiplier 94 is of the type set forth in the above cited patent of Paul K. Weimer and consists of 5 stages of amplification. The collector electrode 95 of the multiplier 94 is substantially a fine mesh screen connected into an amplifying circuit represented by a tube 96.

Writing

The tube of Figure 6 is one which establishes a charge pattern on target 66 corresponding to an optical image projected upon the photocathode film 64. The optical image may be of any type desired. Photoelectrons are emitted from the lighted areas of film 64 and are accelerated and directed onto the target surface 66 at a velocity sufficiently high that they strike the dielectric coat of target 66 at above first cross-over to provide a secondary emission therefrom. The target surface areas where the photoelectrons strike are thus driven to an equilibrium potential which is substantially that of the collector screen 74, and in the manner described above for the tube of Figure 1. The uniform field of coil 72 maintains the photoemission from film 64 in the same relationship as the

light pattern focussed upon the photocathode 64. This, then establishes a charge pattern on the target 66, which closely corresponds to the light pattern focussed upon the photocathode.

Reading

The charge pattern established on target 66 may be continuously "read" by the beam of gun 80, in the manner described above for the tube of Figure 1. The output signal from the multiplier electrode 95 may be utilized to drive an oscilloscope or picture tube so that a visual image may be produced of the charge pattern stored on target 66. This visual picture can be maintained and observed for any desired length of time. The output signal may be removed at the collector screen 74 also, as the electrons of the reading beam which have penetrated the target screen are largely collected by this screen (74).

Erasing

The charge pattern on target 66 can be erased by changing the potential of collector screen 74 to ground so that all secondary emission from the target 66 is suppressed and caused to fall back onto the target surface to drive the surface back to ground potential. In this operation, a uniform light may be directed onto photocathode 64 so that a uniform photoemission will fall on all the target surface to erase the charge pattern.

Holding

With the operating voltages described, the charge pattern established on target 66 may be restored or maintained by raising the photocathode toward ground potential and illuminating it with a uniform light source. By adjustment, the potential of the photocathode can be established at a point where photoelectrons therefrom will stroke the charged areas of target 66 above first cross-over potential and the uncharged areas of the target screen at below first cross-over. This will reestablish the charge pattern on target 66.

Another holding technique is that in which the potential of screen 74 is maintained above first cross-over potential relative to ground during "writing." Then "reading" beam electrons passing through both target screen 66 and collector screen 74 will be repelled by the zero potential field surface in front of the photocathode. Some of these repelled electrons will get back to the target 66 and will be drawn over to the charged target areas to strike at above first cross-over to restore them to equilibrium or collector screen potential. Those electrons falling on the uncharged areas will be below first cross-over and will maintain these areas at ground.

The tube of Figure 6 may be operated at different sets of electrode potential from that indicated in the figure. For example, a tube of the type of Figure 6 was operated with the photocathode 64 at minus 540 volts relative to ground, the accelerating electrode 68 and collector screen 74 at between 24 and 100 volts positive; the target 66 at ground; decelerating mesh 92 at 210 volts positive; wall electrode 90 at 170 volts positive; persuader electrode 93 at 204 volts positive; gun accelerating grid 86-88 at 213 volts positive. The field of coil 72 was adjusted to substantially 80 gauss.

Half-tone operation

If the optical image is maintained for any length of time on photocathode 64, all areas of target 66 struck by photoelectrons will be driven positively to the equilibrium potential established by collecting screen 74. Those areas of target 66 charged by photoelectrons from partially illuminated areas of the photocathode 64 are charged as high as those target areas charged by photoelectrons from brightly illuminated portions of the photocathode. The reading beam, in this case, will resolve the charge pattern and provide as great a signal from those areas charged by photoelectrons from "bright" areas of the photocathode as the signal obtained from those areas of the target

75 charged by photoelectrons from partially illuminated or "gray" areas of the photocathode. Thus, the operation described for the tube does not provide for resolving "gray" areas or half-tones of an image projected on photocathode 64.

To provide half-tone operation of the tube of Figure 6, the optical image projected on photocathode 64 may be only allowed to fall on the tube instantaneously so that the photoemission from the partially illuminated or gray areas of the photocathode is not enough to charge the corresponding areas of target 66 to equilibrium potential, but only to a potential between ground and equilibrium. The reading beam now will lose electrons through target 66 in proportion to the amount of charge on the target areas adjacent the apertures. The return beam to gun 80 will be thus modulated in amount corresponding to the charge established on each area of the target.

Another mode of tube operation to provide half-tone signals is by lowering the potential of accelerating electrode 68 to a point at which reading beam electrons passing through target screen 66 are in part returned to the charged areas of target 66, to drive them down toward ground potential. If the optical picture is maintained on photocathode 64, potentials of screen 74 and of electrode 68 can be found which will return just enough reading beam electrons to those target areas, charged by photoelectrons from the partially illuminated areas of the photocathode, that the potential of these target areas will remain below equilibrium potential. Conditions can be set so that the secondary emission from those target areas charged by photoelectrons from the brightly illuminated areas of the photocathode 64 is just great enough to raise these target areas to equilibrium potential in spite of reading beam electrons falling back on these "bright" areas. Thus there is established on the surface of target 66, facing the photocathode 64, a charge distribution varying in potential, from point to point, from reading beam cutoff to equilibrium potential. The "reading" beam returned to the multiplier 94 will be modulated in accordance to the charge pattern and, thus, resolve the half tones or gray areas of the optical pattern projected on photocathode 64.

What is claimed is:

1. An electron discharge device comprising, a foraminous target electrode sheet having one surface of electrically insulating material, means including an electron emissive cathode for establishing a charge pattern on said insulating target surface, an electron gun spaced from said cathode for forming a beam of electrons, means for scanning said beam over the other surface of said target electrode, and an electrode for collecting beam electrons reflected from said target.

2. An electron discharge device comprising, a foraminous target electrode sheet having one surface of electrically insulating material, an electron gun to provide an electron beam for establishing a charge pattern on said insulating surface of said target, said electron gun including a cathode and a control grid electrode spaced from said target electrode, electrode means between said cathode and target electrode for directing beam electrons from said cathode onto said insulating surface with energies sufficiently large to provide a secondary emission greater than unity from said insulating surface, a first deflecting means for scanning said beam over said target and a collector electrode adjacent said insulating surface of said target to collect secondary electrons from said insulating surface, lead means from said cathode and said control grid electrode to be connected to a signal source for applying signal voltages thereto to modulate said electron beam, means spaced from said target electrode and including an electron source for directing a second beam of electrons adjacent to the charged target surface, a second deflection means positioned between said electron source and said target for sequentially scanning said second beam to different portions of said target to be

modulated thereby, and an electrode for collecting said second modulated electron beam.

3. An electron discharge device comprising, a foraminous target electrode sheet having one surface of electrically insulating material, means including an electron emissive cathode for establishing a charge pattern on said insulating target surface, an electron gun spaced from said cathode including a second cathode for forming a beam of electrons, means for scanning said beam over the other surface of said target electrode, lead means connected to said target sheet for connecting to a potential source whereby said target sheet is maintained near the potential of said gun cathode, and electrode means for collecting beam electrons reflected from and transmitted through said foraminous target.

4. A charge storage device comprising, a target electrode including a conductive foraminous sheet, an electrically insulating material coating one surface of said target sheet, means for establishing a charge pattern on said coated target surface, said means including a source of electrons and electrode means between said electron source and said target sheet for directing electrons from said source onto said coated target surface with energies sufficiently great to provide a secondary emission greater than unity from said target surface, an electron gun spaced from said target sheet for forming a beam of electrons, means for scanning said beam over the other surface of said target sheet, an electrode for collecting beam electrons from said target electrode, a screen reflector mounted between said target electrode and said electron source for repelling said secondary and beam electrons toward said coated target surface.

5. A charge storage device comprising, a target electrode including a conductive foraminous sheet, an electrically insulating material coating one surface of said target sheet, means for establishing a charge pattern on said coated target surface, said means including a source of electrons and electrode means between said electron source and said target sheet for directing electrons from said cathode onto said coated target surface with energies sufficiently great to provide a secondary emission greater than unity from said target surface, an electron gun spaced from said electron source for forming a beam of electrons, means for scanning said beam over the other surface of said target sheet, an electrode for collecting beam electrons from said target electrode, a screen mounted between said target electrode and said electron source for collecting secondary electrons from said coated target surface, and lead means connected to said screen for connecting to a signal source for applying signal voltages thereto for modulating the collection of secondaries from said coated target surface.

6. A charge storage device comprising, a target electrode including a foraminous sheet having an electrically insulating coating over the surface thereof, an electron gun spaced from said target electrode for providing an electron beam for establishing a charge pattern on one surface of said foraminous sheet, electrode means between said electron gun and said target for directing the electron beam from said gun onto said target surface at energies sufficiently great to provide secondary electron emission from said target surface, means for scanning the electron beam from said gun over said target surface, a screen electrode closely spaced from said target surface for collecting the secondary electrons therefrom, and holding means for maintaining the charge pattern on said target surface, said means including said electron gun, said screen electrode and a mounting ring supporting said target sheet across the open center of said ring, said mounting ring having a portion thereof exposed to the scanning of said electron beam, lead means connected to said mounting ring for joining said ring to an electron source whereby a secondary electron emission occurs upon bombardment of said ring by electrons from said gun.

7. An electron discharge device comprising, a target electrode including a foraminous sheet and an electrically insulating coating on the surface of one side of said target sheet, means for establishing a charge pattern on the coated surface of said target sheet, an electron gun facing the other side of said target sheet for forming a beam of electrons, scanning means for directing the electron beam over said target sheet, a screen mounted closely adjacent said one side of said target sheet for directing beam electrons onto said coated target surface to erase said charge pattern.

8. An electron discharge device comprising, a target electrode including a fine mesh conductive screen and an electrically insulating coating on the surface of one side of said screen, means including a cathode electrode spaced from said target electrode for establishing a charge pattern on the coated surface of said target screen, said means including an accelerating electrode between said cathode and target electrodes for directing electrons from said source onto said coated target surface with energies sufficiently great to provide secondary emission from said coated target surface greater than unity, an electron gun facing the other side of said target screen for forming a beam of electrons directed at said other screen side, a second screen mounted adjacent and facing said one side of said target screen for collecting the secondary emission from said coated target surface, and lead means connected to said second screen for connecting said second screen to a low potential to return the secondary emission to said coated target surface for erasing the charge pattern thereon.

9. An electron discharge device comprising, a target electrode including a fine mesh conductive screen and an insulating coating on the surface of one side of said screen, means including a cathode electrode spaced from said target electrode for establishing a charge pattern on the coated surface of said target screen, said means including an accelerating electrode between said cathode and target electrodes for directing electrons from said cathode onto said coated target surface with energies sufficiently great to provide secondary emission from said coated target surface greater than unity, an electron gun including an electron source facing the other side of said target screen for forming a beam of electrons directed at said other screen side, lead means connected to said cathode electrode, said electron source and said conductive screen to join them to sources of substantially the same potential to hold said charge pattern on said target electrode.

10. A charge storage device comprising, a target electrode including a conductive foraminous sheet, an insulating material coating one surface of said target sheet, means for establishing a charge pattern on said coated target surface, said means including a source of electrons and electrode means between said electron source and said target sheet for directing electrons from said source onto said coated target surface with energies sufficiently great to provide a secondary emission greater than unity from said target surface, an electron gun for forming a beam of electrons, means for scanning said beam over the opposite surface of said target sheet, an electrode for collecting beam electrons reflected from said target electrode, a first screen mounted between said target electrode and said electron source collecting said secondary electrons, and a second screen mounted between said first screen and said electron source for reflecting beam electrons passing through said first screen back onto said charged target surface.

11. An electron discharge device comprising, a foraminous target electrode sheet having one surface of insulating material, means including a photoemissive cathode for establishing a charge pattern on said insulating target surface, an electron gun spaced from said photoemissive cathode for forming a beam of electrons, means for scanning said beam over the other surface of said target

electrode, and an electrode for collecting beam electrons from said target.

12. A charge storage device comprising, a target electrode including a conductive foraminous sheet, an insulating material coating one surface of said target sheet, means for establishing a charge pattern on said coated target surface, said means including a photocathode and electrode means between said photocathode and said target sheet for directing electrons from said photocathode onto said coated target surface with energies sufficiently great to provide a secondary emission greater than unity from said target surface, an electron gun spaced from said photocathode for forming a beam of electrons, means for scanning said beam over the other surface of said target sheet, an electrode for collecting beam electrons from said target electrode, a screen mounted between said target electrode and said photocathode for collecting secondary electrons from said coated target surface.

13. An electron discharge device comprising, a foraminous target electrode sheet having one surface of insulating material, means for establishing a charge pattern on said insulating surface of said target, said means including a photocathode spaced from said target electrode, electrode means between said photocathode and target electrode for directing electrons from said photocathode onto said insulating surface with energies sufficiently large to provide a secondary emission greater than unity from said insulating surface, and a collector electrode adjacent said insulating surface of said target to collect secondary electrons from said insulating surface, an electron gun spaced from said photocathode for forming a beam of electrons, means for scanning said beam over the other surface of said target electrode, and an electrode for collecting beam electrons from said target.

14. The method of operating a storage device including a foraminous target electrode sheet having an electrically insulating coating on one surface of said foraminous sheet, said method comprising the steps of establishing a charge pattern on the insulating coating of said target sheet, scanning the other surface of said target sheet with a beam of electrons having low velocities in the region of said target, repelling electrons of said beam penetrating through said foraminous target back onto said insulating coating to erase said charge pattern thereon.

15. The method of operating a storage device including a foraminous target electrode sheet having an electrically insulating coating on one surface of said foraminous sheet, said method comprising the steps of, establishing a charge pattern on the insulating coating of said target sheet, directing electrons onto said target sheet with energies sufficiently great to provide a secondary electron emission greater than unity from said

insulating coating, repelling said secondary electron emission back onto said insulating coating to erase the charge pattern thereon.

16. The method of operating a storage device including a foraminous target electrode sheet having an electrically insulating coating on one surface of said foraminous sheet, said method comprising the steps of, establishing a charge pattern of both high and low relative potentials on said insulating coating of said target sheet, scanning sequentially over a portion of said charged insulating coating electrons having energies sufficient to provide a secondary electron emission of less than unity from portions of said insulating coating at low potentials and a secondary electron emission greater than unity from portions of said insulating coating at high potentials whereby the charge pattern is maintained on said insulating coating.

17. An electron discharge device comprising, a foraminous target electrode sheet having one surface of electrically insulating material, means including a first electron emissive cathode for establishing a charge pattern on said insulating target surface, an electron gun spaced from said cathode including a second cathode for forming a beam of electrons, means for scanning said beam over said target electrode, lead means connected to said target sheet for connecting to a potential source whereby said target sheet is maintained near the potential of said second cathode and electrode means for collecting beam electrons reflected from and transmitted through said foraminous target.

18. The method of operating a storage device including a foraminous target electrode sheet having an electrically insulating coating on one surface of said foraminous sheet, said method comprising the steps of establishing a charge pattern on the insulating coating of said target sheet, scanning said target sheet with a beam of electrons having low velocities in the region of said target, repelling electrons of said beam penetrating through said foraminous target back onto said insulating coating to erase said charge pattern thereon.
